CUTTING AND SHAVING DEVICE

Henry Sieminski, Jersey City, N. J.

Application February 11, 1935, Serial No. 6,082

16 Claims. (Cl. 30—31)

This invention relates to an apparatus for shaving or cutting hair, and has for one of its objects to provide a novel device by means of which hair, growing in parts of the human body ordinarily 5 not accessible, or difficult to reach, such as the nose, nostrils and nasal passages, ears and ear channels, under arms, etc., can be safely removed without danger of cutting the skin or tissues.

More particularly the invention relates to a 10 razor having all of the advantages of a conventional safety razor, but in which the head and blade are of such shape and proportions as to permit and facilitate its use, not only in remote external parts of the body, but in passages and 15 cavities thereof, which may be irregular in shape or small in size. The devices hitherto known for shaving purposes are not adapted for the said mentioned uses, due either to their basic dimensions or shape.

20 The apparatus of this invention is a self contained, complete razor, but it may be utilized as an accessory to safety razors of conventional design, and a further object contemplates a head, blade and holder of such shape and dimensions as 25 will permit utilization of a hollow handle or holder for the usual type of safety razor as a case or container for the device of the present invention.

The structure may include an integral holder and head, with removable means for blade replacement, or the head may be made separable from the handle; in fact, various modifications in the construction, shape, style and design to accord with desired uses are contemplated, several 30 being described herein.

35 To the attainment of the above and other objects, which will appear as the description proceeds, reference may be made to the accompanying drawing, in which:—

40 Fig. 1 is a side elevation of an assembly of the apparatus;

Fig. 2 is an end view looking at the head thereof;

Fig. 3 is a sectional view taken on line 3—3 of Fig. 1;

Fig. 4 is a sectional view taken on the line 4—4 of Fig. 3;

Fig. 5 is a face view of one form of blade;

Fig. 6 is a section on the line 6—6 of Fig. 5;

50 Fig. 7 is a side view of a modified clamping screw;

Fig. 8 is an end view thereof;

Fig. 9 is a side elevation of an assembly of the apparatus illustrating a modified holder, head and clamping screw;

Fig. 10 is an end view looking at the head thereof;

Fig. 11 is a face view of a different form of blade;

Fig. 12 is a section on line 12—12 of Fig. 11; 5 Figs. 13 and 14 are face views of still different forms of blades; and

Fig. 15 is a sectional view of an assembly in which the holder of one razor is utilized as a case for an assembly of the present apparatus, said 10 assembly being slightly modified.

Referring more specifically to the drawing in which like reference numerals designate like parts, it will be observed that the apparatus embodying the invention comprises generally a holder 15 20 25 the blade 30 will be clamped between the head portion 23 and the underside of the screw 27.

The blade 30 is of generally annular shape and dished to provide areas 31 and 32 conforming generally to the portions 25-26 of the head. The angle of inclination in the blade is, however, somewhat smaller than the angle of the surface of the lower part of the head, so that when the apparatus is assembled for use there will be a slight space between the blade and said lower surface, thereby giving the necessary tilt to the blade for an effective cutting angle.

It is not essential that the head of the razor be integral with the neck of the holder, and Fig. 15 illustrates one form of the invention in which the neck 22 is shortened, to be completed by an extension 33 which may be formed integral with the lower portion of the head as indicated at 34. In this form the stem 28 of the clamping screw will 20 extend freely through the portions 33 and 34 to engage the threaded interior of the neck 22.

There is illustrated in Figs. 7 and 8 a modified form of clamping screw which however, as in the case of the element 27, functions to complete the head of the razor. This modified screw 35 is constructed substantially as the screw 27 but with curved grooves or flutes 36 traversing substantially the entire head surface. The grooves may stop in the proximity of the screw or may extend over the entire head surface.

Fig. 9 illustrates a slight modification in the head of the razor from that illustrated in Fig. 1, in which the clamping screw 37 is of lesser diameter than the lower portion 23 of the head, the remainder of the assembly being structurally the same.

These modifications in clamping screw and head structure are advantageous in particular types of work to which the razor is adaptable.

Figs. 11 and 12 illustrate a blade 38 having a substantially oval configuration, Fig. 13 showing a blade 39 modified in configuration from the oval idea and Fig. 14 illustrating a three-sided arched blade 40. Obviously the particular shape of the blade can be carried out to such shapes as a pear, half circular, or any other desired configuration, without departing from the spirit of the invention.

While it is contemplated that an assembly of this nature may be made and used as a complete entity, it may be found desirable to utilize same as an attachment or accessory for the conventional type of safety razor kit now on the market, and to this end, as illustrated in Fig. 15, the usual holder 41 has its handle or grip portion 42 hollowed out and left open at the end. The external diameter of the head 23 and clamping screw 27, as well as the external diameter of the handle portion 21, will be proportioned to substantially 60 equal the internal diameter of the handle portion 42, whereupon the entire assembly 20 may be frictionally fitted into said portion 42, which thereupon functions as a carrying case, without in any way detracting from or affecting the use 65 of the holder 41-42 in its usual manner with a conventional razor head.

In other words, as will be evident from the drawing the head and blade of each form of the invention is symmetrical and the greatest axis of symmetry substantially approximates, in extent, the transverse axis of the holder. This offers in addition to the advantages of permitting insertion within cavities of the ear or nose, the additional advantage specifically shown in Fig. 15, of inserting the entire device, head and handle, within

the hollow grip portion or handle for another razor as described above.

Having thus described the invention, the use and operation thereof will be readily apparent. To assemble the apparatus, a blade will be fitted over the stem of the clamping screw which will be threaded home into the neck of the holder and the apparatus is ready for use, which use consists generally in inserting the head in the particular cavity and withdrawing same to shave or cut hair growing therein.

While selected embodiments of the invention have been illustrated and described herein, it is not intended that same shall be considered as limiting, other than as defined in the appended claims, many variations in size, shape and use being within the range of the herein described invention. For example, while the device has been particularly described as of a shape and size well adapted to use internally of cavities in the human body, it is quite evident that by slight change in size, the device will lend itself to use in other normally inaccessible parts of the human body as under the arms.

Having thus described my invention, what I claim as new and desire to secure by Letters Patent is:

1. A device of the class described, comprising a holder terminating in a head shaped and sized to conform to predetermined characteristics of a cavity of the human body, whereby it may enter completely within such cavity and a cutting blade carried by said head, said head comprising a fluted portion converging from a point adjacent the blade into said holder, and a blade clamping screw threaded into said head.

2. A device of the class described, comprising a holder terminating in a head shaped and sized to conform to predetermined characteristics of a cavity of the human body, whereby it may enter completely within such cavity and a cutting blade carried by said head, said head comprising a fluted portion converging from a point adjacent the blade into said holder, and a blade clamping screw threaded therein, said blade being shaped to encompass said screw between the head of the screw and said fluted portion.

3. A device of the class described, comprising a holder terminating in a head shaped and sized to conform to predetermined characteristics of a cavity of the human body, whereby it may enter completely within such cavity and a cutting blade carried by said head, said head comprising a fluted portion converging from a point adjacent the blade into said holder, and formed with a generally convex seat for the blade, and a blade clamping screw threaded into said head.

4. A device of the class described, comprising a holder terminating in a head shaped and sized to conform to predetermined characteristics of a cavity of the human body, whereby it may enter completely within such cavity and a cutting blade carried by said head, said head comprising a fluted portion converging from a point adjacent the blade into said holder, and formed with a generally convex seat for the blade, said seat having a centrally disposed flat area merging into an outwardly inclined area, and a blade clamping screw threaded into said head, at a point substantially centrally of said flat area.

5. A device of the class described comprising a holder terminating in a head shaped and sized to conform to predetermined characteristics of nasal and aural cavities of the human body, whereby it may enter completely within such

5 cavities and a cutting blade carried by said head, said head comprising a guard portion having flutes disposed about the axis of the head and extending substantially longitudinally thereof, and a blade clamping screw threaded into the guard portion, internally of its fluted periphery.

6. A device of the class described, comprising a holder terminating in a head shaped and sized to conform to predetermined characteristics of a 10 cavity of the human body, whereby it may enter completely within such cavity and a cutting blade carried by said head, said head comprising a fluted portion converging from a point adjacent the blade into said holder, and a blade clamping screw 15 threaded into said head, said screw having flutes disposed about its exterior and conforming to those of said fluted head portion.

7. A device of the class described, comprising a holder terminating in a head shaped and sized 20 to conform to predetermined characteristics of a cavity of the human body, whereby it may enter completely within such cavity and a cutting blade carried by said head, and a blade clamping screw threaded into said head, said screw having flutes 25 exteriorly disposed about its axis, said flutes extending substantially longitudinally thereof, and the walls thereof tapering inwardly from a point adjacent the blade toward said holder.

8. A razor comprising a holder terminating in 30 a symmetrical head comprising a cap and guard shaped to conform to predetermined characteristics of aural and nasal cavities of a human body, whereby it may enter substantially completely within such cavities, said head having its 35 greatest axis of symmetry approximating in extent the transverse axis of the holder.

9. A razor comprising a holder terminating in a symmetrical head comprising a cap and guard, shaped to conform to predetermined characteristics 40 of aural and nasal cavities of a human body, whereby it may enter substantially completely within such cavities, said head having its greatest axis of symmetry approximating in extent the transverse axis of the holder, and a substantially cylindrical case therefor having a 45 transverse diameter slightly in excess of the said axis of symmetry of said head.

10. An adjunct to a safety razor having a hollow handle comprising a holder terminating in a 50 symmetrical head comprising a cap and guard, shaped to conform to predetermined characteristics of aural and nasal cavities of a human body, said head having its greatest axis of symmetry approximating in extent that of the 55 holder, said razor being proportioned to fit within said hollow handle whereby said hollow handle forms a carrying case.

11. A device of the class described, comprising 60 a holder terminating in a head shaped and sized to conform to predetermined characteristics of

aural and nasal cavities of the human body, whereby it may enter completely within such cavities and a cutting blade carried by said head, said head comprising a fluted portion converging from a point adjacent the blade 5 into said holder, and a blade clamping screw threaded therein, the greatest diameter of the head of the screw being less than the greatest diameter of the fluted portion of the head.

12. A device of the class described comprising 10 a holder terminating in a head shaped and sized to conform to predetermined characteristics of a cavity of the human body, whereby it may enter completely within such cavity and a cutting blade carried by said head, said head comprising a 15 fluted portion converging from a point adjacent the blade into said holder, and detachable therefrom, and a blade clamping screw extending therethrough and threaded into said holder.

13. A device of the class described, comprising 20 a holder terminating in a head of generally circular shape in cross section, and having a substantially convex blade seating surface, a cutting blade carried by said head and conforming to the shape thereof, a blade clamping screw extending 25 through said cutting blade, and a guard for said blade tapering from a point adjacent the blade inwardly to said holder.

14. A razor, shaped and sized to enter aural and 30 nasal cavities of the human body comprising a 30 holder terminating in a head of generally triangular shape in cross section, and having a substantially convex blade seating surface, a cutting blade carried by said head and conforming to the 35 shape thereof, a blade clamping screw extending through said cutting blade, and a guard for said blade tapering from a point adjacent the blade inwardly to said holder.

15. A razor, shaped and sized to enter aural and 40 nasal cavities of the human body, comprising a 40 holder terminating in a head of generally oval shape in cross section, and having a substantially convex blade seating surface, a cutting blade carried by said head and conforming to the shape thereof, a blade clamping screw extending 45 through said cutting blade, and a guard for said blade tapering from a point adjacent the blade inwardly to said holder.

16. A device of the class described comprising 50 a holder terminating in a head shaped and sized to conform to predetermined characteristics of a cavity of the human body, whereby it may enter completely within such cavity and a cutting blade carried by said head, said head comprising a fluted portion converging from a point adjacent 55 the blade into said holder, the sides of the flutes converging toward the holder, and a blade clamping screw threaded therein.
